UNITED STATES PATENT OFFICE.

CHARLES B. NICHOLS, OF WASHINGTON, DISTRICT OF COLUMBIA, ASSIGNEE, BY DIRECT AND MESNE ASSIGNMENTS, TO THE NICHOLS AEROPLANE COMPANY, A CORPORATION OF ARIZONA.

HEAVIER-THAN-AIR FLYING-MACHINE.

1,134,756.

Specification of Letters Patent.

Patented Apr. 6, 1915.

Application filed September 25, 1909. Serial No. 519,592.

To all whom it may concern:

Be it known that I, CHARLES B. NICHOLS, a citizen of the United States, and a resident of Washington, in the District of Columbia, have invented certain new and useful Improvements in Heavier-Than-Air Flying-Machines, of which the following is a specification.

This invention relates generally to the art 10 of aeronautics and specifically to a flying machine having an extremely flexible control.

The principal object of the invention is to construct a flying machine in which the 15 various guiding and balancing devices act simultaneously to produce a unified result.

A further object of the invention is to provide balancing and guiding devices which may be bodily moved with reference to the 20 supporting planes of the flying machine and thus utilize the weight of the guiding device to assist in changing the direction of movement when the flying machine is in flight.

25 Another object of the invention is to provide a heavier than air flying machine having its supporting plane, or aero-plane, pivotally mounted to the frame work in such manner that the angle of incidence of the 30 plane may be changed with reference to the frame work of the machine.

The invention also includes novel steering 35 mechanism which enables the operator to simultaneously adjust the horizontal rudders, the tail and the aero-plane itself; to adjust the tail and the horizontal rudders simultaneously, the aero-plane being stationary with reference to the frame of the machine; or to adjust the front plane or the 40 horizontal rudder alone.

Another object of the invention is to construct a flying machine which may be started and alighted upon water, as well as on land, and therefore the invention includes the 45 combination of an aero-plane with a novel form of a boat.

A further object of the invention is to provide a mechanism whereby oil may be ejected beneath the boat as the machine is 50 moving forward through the water during the commencement of its flight, thus lessening skin friction.

A still further object of the invention is to provide an aero-plane having its supporting 55 surface formed in such manner as to

tend to prevent lateral movement of the aero-plane through the air and to prevent "side-wise movement or skidding."

This invention, which is believed to be broadly new, is for this reason susceptible of 60 structural changes without departing from the scope thereof, but a preferred form will be hereinafter specifically described by reference to the drawings, and the scope of the invention will be indicated by the claims. 65

In the accompanying drawings, in which like numerals represent like parts throughout the several figures:—Fig. 1 is a plan view of the flying machine. Fig. 2 is a perspective view from the front of the machine. Fig. 3 is a longitudinal sectional elevation through the center line of Fig. 1. Fig. 4 is a transverse sectional elevation through the transverse center of the machine. Fig. 5 is a diagrammatic view showing method of adjusting the various planes. Fig. 6 is a detail showing the steering levers. Fig. 7 is a detail of the rack and pinion for controlling the aero-plane. Fig. 8 is a detail elevation of the steering pulleys. Fig. 9 is a detail 70 view of the front vertical rudder. Fig. 10 is a detail showing the oil reservoir in section. Fig. 11 is a detail of the oil discharge device. 75

Referring more particularly to Figs. 1, 2 80 and 3, the flying machine comprises an aero-plane, (or supporting plane) a frame work carrying the mechanism, and front and rear guiding planes. The front guiding plane comprises a horizontal and a vertical rudder. The rear guiding plane comprises a tail which is formed of a horizontal curved wing having a vertical plane rigidly attached thereupon. The frame-work, which 85 carries the machinery for driving the machine and the control mechanism, is formed in the shape of a boat, and to the upper structure of this frame work the aero-plane is pivotally mounted in such manner that it 90 may be adjusted in order to present different angles of incidence as the machine is driven through the air. 95

Referring more specifically to Fig. 3, the aero-plane frame is pivoted as at 2 to the main frame 3. The link 4 projects downward and has its lower end formed into an open slot, one side of which is constructed with the rack which is adapted to engage a small pinion 5 for a purpose which will be hereinafter more specifically described. 100 105 110

The frame 3 carries bearings 6 in which the propeller shafts 7 are mounted. The propellers 8 are mounted on the shafts 7 and are arranged in front of the aeroplane 1. 5 The propeller shafts 7 are mounted upon the frame 3 on a horizontal line with the center of resistance of the machine, the center of resistance being understood to mean the mathematical line which forms the center of equilibrium with reference to the forward flight of the machine. From the upright main frame 3^a a rearwardly projecting strut 9 connects with the frame-work of the boat and thus forms a rigid support for 10 the propellers and for the attachment of the aeroplane to the frame-work. The boat frame is continued forward and forms a frame-work for supporting the forward plane. In the forward portion of this 15 frame-work a vertical guiding plane 10 is mounted upon an axle 11, which terminates at its lower end in a journal bearing 12 that is mounted upon the axle 15 of the horizontal rudder 14. The journal bearing 12 20 is loosely mounted upon the axle 15 in such manner that the axle may turn without effecting any twisting movement upon the journal 12. Thus it will be seen that the vertical rudder 10 is mounted on a longitudinal center line of the horizontal rudder 14, 25 in such manner that movements of the horizontal rudder do not affect the relationship of the vertical rudder. 30

To the upper end of the axle 11 of the vertical rudder 10 is attached a cross piece 16 to which control cable 17 is attached, and from this cross piece it is carried rearwardly into the boat portion of the machine to steering mechanism, which will be hereinafter 35 more specifically described. The axle 15 of the horizontal rudder 14 is also provided with a cross piece 18 to which is attached the control cable 19 that is also carried into the boat portion of the machine to the steering mechanism. 40

The motor 20 is located in the forward portion of the boat, and is provided with a sheaved drum, or driving pulley 21, over which the driving cables 22 run to the pulleys 24 on the propeller shafts 7. The exhaust for the engine is carried rearwardly, and terminates in a downwardly curved tube 25, which projects from the boat just above the water line when the boat is in the water. The downward direction of this tube 25 enables the gases, which are ejected from the exhaust of the engine, to strike upon the water, and by the re-action from the flow of the gas, to tend in a slight measure to assist the boat and the machine in its forward movement during the moment of starting. 55

Beneath the foot rest 26 is carried a reservoir 27, which is adapted to be filled with oil. Projecting from the foot rest is a small 60

pneumatic foot pump, which enables the operator to compress the air within the oil reservoir and thus force the oil through the tube 28, out into a discharge tube 29 which is arranged longitudinally across the bow of the boat. This tube 29 is provided at intervals with small openings 30 in order to distribute the oil uniformly over the water, at and under the front of the boat, the object of this oil supply being to enable the operator to eject oil upon the water at the moment when the propellers are started, thus quieting the wave motion of the water and also tending to lessen the skin friction between the boat and the surface of the water during the time when the machine is gaining sufficient velocity to enable it to rise from the water and begin its flight in the air. 75 80 85

The aviator's seat 31 is located back of the motor 20, and is attached by means of the supports 32 to the frame-work of the machine. The rear portion of the boat terminates in parallel members 34 which are curved with reference to the horizontal plane. The tail 35, is provided with members 36, that are slidable upon this parallel frame. The rear portion of the frame carries a pulley 37 over which the control cable 38 is adapted to pass. This cable is continuous, and passes around the operating pulley or drum 39, which will hereinafter be more specifically described. The small pulleys 40 are for the purpose of guiding the cable 38. 90 95 100

The front vertical rudder 10 is formed in the shape of a plane. The horizontal guiding rudder 14 is formed with its surface having a slight downward curve at the rear of the rudder. The tail member 35 is formed with a frame-work which carries varnished or vulcanized silk, which is stretched upon the frame-work in such manner as to have a curvature both in longitudinal and lateral direction. The vertical member 41 is rigidly attached on the longitudinal center line of the tail and is in the form of a plane. This vertical plane 41 is immovable with reference to the tail itself. 110

Referring more specifically to Figs. 3, 5, 6, 7 and 8 the steering mechanism, for an up and down direction, consists of mechanism whereby any one of the horizontal planes including the aeroplane itself, may be adjusted either independently or in combination with any other horizontal plane. That is, the aeroplane may be adjusted to a certain angle of incidence, and the front horizontal rudder and tail controlled independently of the adjustment of the aeroplane; the tail may be adjusted with a definite angle of incidence, and the front plane may be controlled independently of either the aeroplane or the tail; and lastly the aeroplane, front rudder and tail may be simulta- 115 120 125 130

neously adjusted to varying relations. This single, multiple, or combined control is effected by means of three levers. The shaft 42 is mounted upon bearings 44 which are carried by the boat structure. The gear 5 is rigidly mounted upon the shaft 42 and engages the rack 45 in the link 4 which is pivoted to the aeroplane frame at 46. The member 47, opposite the rack, prevents the 10 rack from leaving the gear wheel. To the right end of the shaft 42 the three element control lever 48 is rigidly mounted and co-operates with a notched segment 49 that is mounted upon the frame-work of the boat. 15 I have designated the lever 48 as a three element control lever for the reason that this lever when operated, moves the horizontal front rudder, the aeroplane and the tail. The two control lever 50 is rigidly mounted 20 upon a large pulley 39, which is loose to turn upon the shaft 42. This lever 50 engages the segment 51 which is fixedly attached to the shaft 42. The one lever control 52 is fixedly mounted upon a small pulley 53, 25 which carries the cable running to the front horizontal rudder, and co-operates with the segment 54 that is fixedly mounted upon the large pulley 39. It will be seen that if the three control lever 48 be operated, it will 30 turn the shaft 42, and therefore will move all of the parts that are in fixed engagement with the shaft. Since the two control lever 50 engages the segment rigidly mounted upon the shaft 42, and the one control lever 35 52 engages the segment on the two control lever 50, it will be seen that when the three control lever 48 is operated, both the levers 50 and 52 will be moved with the shaft 42, since the two control lever is in engagement 40 with the segment carried upon this shaft. Thus the aeroplane, the front horizontal rudders 14 and the tail 35 will all be simultaneously adjusted, and the aviator is enabled to quickly adapt his machine to conditions which may arise due to striking an abrupt change in varying air currents. By operating the two control lever 50 it will be seen that since the three control lever is in engagement with the segment 49 mounted on 50 the side of the boat, that the shaft 42 will not be moved by the two control lever 50. Therefore the aeroplane will not be changed with reference to the position it may be in relative to the frame-work of the machine. 55 But since the one control lever 52 engages the segment 54, carried upon the pulley 39, that is attached to the two control lever 50, it follows that when the two control lever is operated it adjusts both the tail and the forward rudder simultaneously. Lastly the one control lever is attached to the pulley 53 which controls the front horizontal plane. Therefore, the operation of this lever will move only the front guiding plane. 60 65 It will be seen that the aviator is given a

great range of vertical control over the machine, and the various vertical controls of the planes may be set in any one position, either during flight or before the flight is commenced.

The cable 19 is attached to one end of the cross piece 18 that is fixedly mounted upon the axle 15 which carries the front horizontal rudder. This cable passes around the small pulley 53 that is mounted upon the shaft 42, and is attached to the other end of the cross piece 18 on the horizontal rudder axle 15. Thus it will be seen that by rotating the pulley 53, the angle of incidence of the front rudder is controlled.

The rear cable 38 is attached to the forward slide 36 upon the tail 35, and passes forwardly into the boat and around the large pulley 39, thence back out over the rear of the boat and around the small pulley 37 that is carried on the outer end of the frame-work 34 upon which the tail slides. By turning the pulley 39 it will be seen that the tail 35 is slid upon the curved frame-work 34. Thus the angle of incidence of the tail is changed as it moves forward or back upon the curved frame, and simultaneously the tail is moved either toward or away from the boat structure. When the machine is in flight, the center of support may be considered as being in a line lying beneath the aeroplane, and this line may be also considered as the aero-pivot about which the machine will oscillate in its up and down change of direction, as hereinbefore described. In moving the tail forward or away from this aero-pivot, the weight of the tail will tend to oscillate the machine about this imaginary line after the manner of the weight upon a scale beam. The arrangements of the pulleys 39, 53 and the cables 18, 38 are such that when the angle of incidence of the front plane is increased in an upward direction, the tail is moved backwardly away from the aero-pivot and the weight will tend to tip the front of the machine up and the rear down. Simultaneously the angle of incidence of the tail is changed, and the tail therefore presents itself at a greater angle to the air through which it is moving. Thus except for the weight of the tail being displaced to a greater distance from the aero-pivot, the effect of the air resistance upon the front plane and upon the tail would be to cause the machine to rise upon an even keel. Should it be desirable that the machine take an upward curve, then the front rudder may be actuated alone. In this case the tail remains stationary and the machine will rise upwardly under the direction of the front rudder and will describe an upward curve.

The vertical rudder 10 is operated by means of the lever 55 which is rigidly attached to the pulley wheel 56 and which is

70

115

120

125

130

loosely mounted upon the shaft 42. The lever 55 is adapted to coöperate with the segment 57 that is fixedly mounted upon the frame-work of the boat. The pulley wheel 56 is connected to the front vertical rudder 10 by means of the cable 17.

As it may not always be expedient for the aviator to arise from the water or alight upon the water, the boat is provided with 10 flexible spring steel runners that extend a sufficient distance beneath the bottom of the boat to prevent the hull of the boat from being crushed when the flying machine alights upon land. The spring steel runners 58 are 15 attached to the front of the boat frame as at 59, and to the rear of the boat frame as at 60.

The aeroplane 1 is formed of a frame-work 61, upon which are mounted longitudinal ribs 62. The frame-work 61 is depressed in the middle and curved outwardly 20 symmetrically from the center line to form the supporting wings for the flying machine. The ribs 62 are upwardly curved between the frame 61 and the transverse bar 25 64, and are downwardly curved after passing the bar 64 in their rearward direction. The frame 61, 64 and the ribs 62 when covered with varnished or vulcanized silk, or any other flexible, suitable material, form 30 the supporting plane. The portion of the aeroplane 1, which lies between the frame 61 and the bar 64, is smoothly covered by the covered material. The portion of the aeroplane to the rear of the bar 64 is arranged 35 such that the material may form itself into longitudinal air pockets when the machine is in flight. In order to be able to accomplish this result a V-shaped piece of material is inserted between each of the longitudinal ribs. This insertion permits the 40 front edge of the after portion of the aeroplane, that is, the edge immediately in the rear of the transverse bar 64, to be smooth and to permit the rear edge of the aeroplane 45 to present corrugations to the air through which the aeroplane is moved. The effect of a wing or aeroplane made upon this pattern is to give it all of the supporting value of a smooth plane and at the same time to make 50 a plane which tends to keep its motion in a forward direction, and not to skid laterally when the aeroplane is being controlled to maintain balance. The air which passes beneath the aeroplane is more or less condensed and as it passes out under the rear portion of the aeroplane the corrugations tend to each form an individual passage for the escape of the condensed gaseous medium. The effect of these individualized 55 currents of air is to cause the plane to maintain an even balance, and gives an effect very similar to that obtained by the feathers in the wing of an eagle.

Throughout the specification the words 60 vertical and horizontal as applied to the va-

rious planes and rudders has reference to the position in which the rudder or plane may lie when the machine is in normal position, and does not refer to the direction in which the rudder or plane would cause the machine to travel when its angle of incidence is changed.

In the drawings which accompany this specification, the various bracing and trussing by means of wire cables and turn-buckles has been omitted for the reason that such bracing is well known in the art and does not form a part of the herein described invention, therefore this unnecessary complication of lines upon the drawings has 80 been omitted for the sake of clearness.

As many changes could be made in the above described structure and many widely different embodiments of this invention could be made without departing from the scope thereof, the definite matter contained in the above description and shown in the accompanying drawings is to be taken as 85 illustrative and not in its limiting sense. I desire it also to be understood that the language used in the claims is intended to cover all of the generic and specific features of this invention herein described and all statements of the scope of the invention which as a matter of language might fall therebetween.

Having described my invention what I claim is:—

1. In a flying machine, the combination with an aeroplane, a horizontal front rudder, a slidably mounted tail, and means for operatively connecting said front rudder with said tail.

2. In a flying machine, the combination of a horizontal front rudder, a tail, a curved frame upon which the tail is slidably mounted, means operatively connecting said horizontal rudder with said tail in such manner as to slide said tail upon the curved frame when said front rudder is operated.

3. In a flying machine, the combination with a pivoted aeroplane, a front rudder, a rear horizontal tail, operative means connecting said pivoted aeroplane, said horizontal rudder and said tail in such manner that they all may be adjusted simultaneously.

4. In a flying machine, the combination of a framework, an aeroplane pivoted to said frame-work, a front horizontal rudder, a rear horizontal tail, and means operatively connecting the aeroplane, the horizontal rudder and the tail in such manner that they may all be adjusted simultaneously.

5. In a flying machine, the combination with a frame-work, an aeroplane pivoted to said frame-work, a horizontal rudder, a tail, operative means connecting said rudder and said tail, and means connecting said aeroplane with the operative means in such man-

BEST AVAILABLE COPY

1,134,756

5

ner that the horizontal rudder, the aeroplane and the tail may be simultaneously adjusted to different angles of incidence.

6. In a flying machine, the combination 5 with an aeroplane of a horizontal rudder, a rear horizontal tail and means for simultaneously moving said tail toward the aeroplane when the said horizontal rudder is declined in a forward direction.

10 7. In a flying machine, the combination with an aeroplane, a horizontal rudder, a rear horizontal tail and means for simultaneously moving said tail away from the aeroplane when the horizontal rudder is inclined in a forward direction.

15 8. In a flying machine, the combination with a pivoted aeroplane, a horizontal rudder, a tail, and means for simultaneously moving the tail in a longitudinal direction when the aeroplane is turned on its pivot.

20 9. In a flying machine, the combination with an aeroplane, a front horizontal rudder, a rear horizontal tail, and means operatively connecting said front rudder with said tail, said operative means comprising flexible cables connecting said tail and a large pulley around which said cables pass, flexible cables connected to said horizontal rudder, a shaft, said pulleys loosely mounted 25 on said shaft, a lever connected to said pulleys, and a segment rigidly attached to said shaft, substantially as described.

30 10. In a flying machine, the combination with a frame-work, an aeroplane pivotally mounted upon said frame-work, a horizontal front rudder, a horizontal tail, means for simultaneously adjusting the aeroplane, the horizontal front rudder and the tail, said means including a shaft, a gear rigidly

35 40 mounted on said shaft, a rack operatively connected with the aeroplane and meshing with said gear, an operating lever fixedly attached to said shaft, a segment attached to said frame-work and coöperating with 45 said lever, substantially as described.

45 11. In a flying machine, the combination with a frame of an aeroplane pivotally mounted upon said frame, a horizontal rudder, a horizontal tail, operative means connecting the aeroplane and the rudder, said

50 means comprising a shaft, a gear fixedly mounted upon said shaft, a rack engaging said gear and operatively connected with the aeroplane, pulley wheels loosely mount-

ed upon said shaft, a lever fixedly attached 55 to one of said pulley wheels, a segment rigidly attached to said shaft and coöperating with said lever.

12. In a flying machine, the combination 60 with a frame, of an aeroplane pivotally mounted upon said frame, a horizontal rudder, a horizontal tail, operative means connecting the aeroplane, the rudder and the tail, said means comprising a shaft, a gear

fixedly mounted upon said shaft, a rack engaging said gear and operatively connected with the aeroplane, a segment rigidly attached to said shaft, a pulley wheel loosely mounted upon said shaft and operatively connected with the tail, a lever rigidly attached to said pulley, a second pulley 70 loosely mounted upon said shaft, a segment mounted upon said first mentioned pulley, a lever rigidly attached to said second mentioned pulley, said second mentioned pulley 75 being operatively connected with said rudder, substantially as described.

13. In a flying machine, the combination 80 with a pivoted aeroplane, a front horizontal rudder, a front vertical rudder, a rear horizontal tail, a vertical plane fixedly mounted upon said tail, means to operate said vertical rudder, and operative means connect-

85 ing said horizontal rudder with said tail in such manner as to adapt said horizontal rudder and said tail to be moved simultaneously, said tail being moved away from said aeroplane when the horizontal rudder is inclined upward and being moved toward said aeroplane when said horizontal rudder is 90 tipped downward.

14. In a flying machine, the combination 95 of a supporting plane, a front horizontal rudder, a rear horizontal tail, means for independently adjusting the effective angle of said rudder and said tail with respect to each other, and means for simultaneously operating said rudder and said tail from their adjusted positions, said last mentioned means comprising a shaft, pulleys rotatably mounted on said shaft, operative means connecting said pulleys with said rudder and tail, and a lever for rotating said pulleys.

CHARLES B. NICHOLS.
